UNITED STATES PATENT OFFICE.

JOHN F. KELLY, OF TRENTON, NEW JERSEY, ASSIGNOR TO THOMAS MADDOCK'S SONS COMPANY, OF TRENTON, NEW JERSEY, A CORPORATION OF NEW JERSEY.

WATER-CLOSET.

1,155,661.

Specification of Letters Patent.

Patented Oct. 5, 1915.

Application filed March 14, 1911. Serial No. 614,382.

To all whom it may concern:

Be it known that I, JOHN F. KELLY, a citizen of the United States, and a resident of Trenton, in the county of Mercer and 5 State of New Jersey, have invented certain new and useful Improvements in Water-Closets, of which the following is a specification.

My present invention relates to water 10 closets and has for its object to eliminate the noise due to the inrush of water when operating the closet, especially in the constructions wherein a flushing valve is provided at the closet to control the supply of water 15 thereto.

My invention is particularly useful in systems wherein a common cistern or source of supply is employed to supply water direct to a number of closets through a flushing 20 valve located at each closet as in such systems the water is necessarily under a heavy pressure at the valve and therefore when admitted to the closet, the water enters with a great rush and in the constructions now 25 in general use causes considerable noise.

My invention makes special provision for 30 breaking the force of the water before it is delivered to the closet thus overcoming a very objectionable feature present in systems employing such flushing valves, that is the force with which the water is admitted to the bowl both for supplying water to the flushing rim and to the siphon jet.

The invention consists in the improved 35 water closet, combinations of parts and details of construction hereinafter more particularly described and then specified in the claims.

In the accompanying drawings Figure 1 40 illustrates a plan view of a water closet embodying my present invention. Fig. 2 is a central vertical section through the same. Fig. 3 is a transverse vertical section taken on the irregular line 3, 3, Fig. 1.

The water closet shown in the drawings 45 is, as regards the construction of the bowl, siphon jet discharge and flushing rim, of the usual well known type but it is to be understood that the invention consists in the manner of supplying the water to the closet and in the construction of the flushing valve casing whereby the force of the inrushing water is dissipated and that the 50 other features of the closet may be widely varied or modified without departing from

the spirit of the invention as recited in the appended claims.

Referring to the drawings, 1 indicates the bowl proper of the water closet which is provided with a flushing rim 2 of any suitable style and having a downwardly disposed opening 3 through which the water circulating around the rim passes to wash down the sides of the bowl as is usual and well known in the art. 4 indicates a chamber formed in the rear of the closet and connected to the passage 5 in the rim 2 by a channel 6 through which channel the water passes from the chamber 4 to the rim.

7 indicates the water supply inlet for the 70 closet. The water for operating the closet is delivered to the inlet 7 from any suitable source of supply and enters a passage 8 located below the upward leg 9 of the siphon 9, 10, the inlet opening 7 being located below 75 the level 11 of the body of water contained in the bowl 1. The passage 8 communicates with an upwardly projecting nozzle or jet 12 adapted to deliver a jet of water from the passage 8 in the direction of the leg 9 of 80 the siphon to assist in emptying the bowl 1 by force combined with the suction of the siphon 9, 10. The passage 8 also communicates with the chamber 4 in back of the flushing rim 2 by a duct 13. (see Fig. 3) 85 through which some of the water delivered by the inlet 7 to the passage 8 is conducted to said chamber. The water being admitted to the passage 8 gradually rises in the duct 13 and into the chamber 4 expelling the air 90 located in the chamber and passageway 5 of the rim ahead of it through the annular opening 3 of the rim, so that the water falls more or less gently through the opening 3 and down the sides of the bowl. As the 95 water is not admitted to the chamber 4 direct it is not conducted into the passageway 5 with the great force and commotion usually present but first gradually pushes the air in the passage out ahead of it preventing any noisy mixing of the air and water and the usual hissing noise attendant upon its discharge through the opening 3 is eliminated, the noise being also further eliminated by depriving the water of considerable of its force, but sufficient force or pressure is maintained to retain the washing effect on the sides of the bowl.

15 indicates an extension from the side of the water closet and preferably integral 110

therewith. The extension forms a housing for a flushing valve adapted to control the supply of water to the closet inlet 7. The valve, the casing of which is indicated at 16, 5 might be of any suitable or desired style and is herein typified as the well known oil regulated valve whose inlet, indicated at 17, is suitably connected to the source of supply. The outlet 18 of the flushing valve is located to discharge in a pocket 19 suitably 10 formed in the housing 15, and which, except for the inlet 7 to the closet, is made watertight. By preference, so as to completely break the shock due to the force of the water 15 before it enters the bowl, the discharge of water from the outlet 18 points in a different direction than the outlet of water from the inlet 7 to the closet.

The inlet passage 7 for the closet also 20 forms the outlet from the pocket 19 and establishes communication between the pocket 19 and passage 8 so that water delivered to the pocket in the valve casing will be conducted to the passage 8 through the 25 inlet 7.

As in the systems above referred to the water must necessarily be under a heavy pressure at the valve to insure successful 30 operation, the outlet 18 preferably discharges against an imperforate wall of the pocket 19 so that its force is considerably reduced when entering the passage 8, the pocket being formed water-tight at the top and bottom to prevent escape or leakage of 35 the water at any place except the inlet passage 7. The flushing valve is provided with the usual operating push-button 20.

It is to be understood that I do not limit 40 myself to the exact details of construction shown and described but various modifica-

tions and equivalents might be resorted to without departing from the spirit of the invention as set forth in the appended claims.

What I claim as my invention is:

1. In a water closet, the combination of a 45 bowl, an extension at the side thereof provided with a water-tight pocket having an outlet communicating with said bowl, a valve casing in said extension the outlet of which is located in said pocket at a distance 50 from and discharging horizontally and directly against the vertical side walls of said pocket to break the force of the water, the outlet of said valve casing being remote from and pointing in a different direction 55 than the outlet from the pocket to the bowl.

2. In a water closet, the combination with a bowl provided with a flushing rim, a water supply inlet, an extension at the side of said bowl provided with a water-tight 60 pocket communicating with said supply inlet, a valve casing mounted in said pocket and having a direct connection with the source of supply and having a discharge passage located in said pocket and adapted 65 to direct the water laterally against the walls thereof in close proximity to the discharge passage of the casing and means for conducting water from said inlet to said flushing rim, the direction of discharge 70 from the valve casing discharge passage being different than that from the water supply inlet to the bowl.

Signed at Trenton in the county of Mercer and State of New Jersey this seventh day of March A. D. 1911.

JOHN F. KELLY.
